UNITED STATES PATENT OFFICE.

CHARLES F. BOND, OF COULEE CITY, WASHINGTON.

CONCRETE MOLD.

1,407,246.

Specification of Letters Patent. Patented Feb. 21, 1922.

Application filed October 5, 1920. Serial No. 414,853.

To all whom it may concern:

Be it known that I, CHARLES F. BOND, a citizen of the United States, residing at Coulee City, in Grant County, and State of Washington, have invented certain new and useful Improvements in Concrete Molds, of which the following is a specification.

My present invention relates to improvements in concrete molds designed especially 10 as implements for forming concrete headers about the ends of a drain pipe that is in situ and used as a culvert or for drainage across highways, the headers being utilized to direct the flow of water to and from the 15 pipe ends, and to prevent erosion of earth at the ends of the culvert or pipe.

The primary object of the invention is the provision of a portable mold device that is comparatively inexpensive in cost of production, foldable in order that it may be compacted and thus stored or transported, and which may be assembled or dismantled 20 with facility for removal from the completed header when the latter has become 25 set.

The mold is patterned and of such shape as to provide a main vertical wall located transversely of the longitudinal axis of the pipe, and a pair of integral, outwardly flaring wings which converge toward the open 30 end of the pipe to direct the flow of water thereto, or to permit the egress of water therefrom. In molding the header, the portable mold is designed to be fitted over the 35 end of the pipe, if desired, and the plastic concrete tamped into the mold, or the header may be molded in the device apart from the pipe, provision being made for an opening in the main wall of the header to subse- 40 quently receive the drain pipe.

In the accompanying drawings I have illustrated one complete example of the physical embodiment of my invention wherein the parts of the foldable or knock down 45 mold are combined and arranged according to the best mode I have thus far devised for the practical application of the principles of my invention.

Figure 1 is a perspective view of a mold 50 constructed according to my invention, as seen from the front, with the parts assembled to receive the concrete or other plastic material.

Figure 2 is a top plan view showing the 55 mold applied to a pipe end and ready for

pouring the material therein for the formation of the header about the pipe end.

In the preferred form of my invention as illustrated in the drawings I utilize sheet metal plates that are hinged and braced together, and these plates may be folded into compact form for transporting to and from the place of work. The assembled mold is erected upon a suitable support as A which may be made up of boards, to form a base, 60 or this base may be a permanent cement or concrete structure forming a foundation for the header to be molded thereon.

The mold is designed to form a vertical wall and two diverging wings, and for this 70 purpose I provide a rectangular form, standing erect, and comprising the rear plates 1 and 2, which are bolted together at their vertical adjoining edges to form a seam 3, and these plates, which form a 75 rigid rear wall for the mold, are provided with semi-circular openings to provide a circular orifice to fit around the pipe 4, as indicated in dotted lines at 5 in Figure 1.

The plates 1 and 2 at their seam 3 are 80 flanged, and secured together by bolts 6 to present an inner smooth wall for the concrete, and the pipe extends through the rear wall of the mold and contacts with the inner face of the front, integral plate 7, to prevent 85 flow of material into the pipe end while pouring the concrete. The single plate 7 may be reinforced by means of the vertical brace bar 8 riveted thereto on its exterior, and the parallel rear wall and front wall 90 of the main portion of the mold are joined by end walls 9 and 10. The front and rear walls and end walls are connected by hinge joints 11, through which the hinge rods or bars 12 are passed, and it will be apparent 95 that by removal of some or all of these rods the several sections may be separated and piled or folded into compact arrangement for storing or transportation.

At their upper and lower edges these 100 plates are bent outwardly to form reinforcing or strengthening flanges 13 to insure rigidity in the structure.

At the ends, the front plate 5 is cutaway as at B in Figure 1 to provide an opening 105 extending from the bottom of the plate a considerable distance to near the top portion of the plate, and in connection with these two openings a pair of complementary wing molds are associated with the main portion 110

of the device in order to form a pair of diverging, integral wings from the main wall of the header that is formed in the main section of the molding device.

5 These wings have vertical hinge joints 14 at their respective inner sides and are joined to the front plate by hinge rods 15, and each mold wing comprises an inner wall 16, an outer wall 17 and an end wall 18 rigidly 10 locked together with a top plate 19. The sides and ends of the wings have hinge joints 20, but the sides 17, or outer sides of the wings, contact with the corners of the main mold.

15 The sectional members of the wings are also fashioned with upper and lower reinforcing flanges 21, and the top plates 19 are bolted or secured to the walls of the wings by bolts or screws 22 passed through the 20 edges of these top plates, which are perforated for the purpose, and the perforated top flanges of the wing sections.

The wing molds are rigidly held to the main mold section by means of two pairs of 25 braces or arms 23 and 24, the former extending from the front wall 5 to the inner sides of the wings, and the latter extending from the end walls of the main mold section to the outer sides of the wings of the mold.

30 For quick action in attaching or detaching the inner diagonally extending braces 23, I provide these metal straps with the end ears 25 which may be slipped over the top end of the pins 26 secured on the wing sides 35 16 and on the front plate respectively. The outer brace arms 24 are detachably connected at 27 and 28 respectively to the end walls of the main section and to the outer sides of the wing sections.

40 In pouring the material into the erected mold device, the plastic concrete is placed in the spaces formed by the wings of the mold and the main section thereof, tamped,

and allowed to set. The material is forced into the wings and packed around the pipe 45 end in the main section to form a solid wall about the pipe with diverging wings extending from the front of the main wall. After the material is set, the mold may be withdrawn by first pulling out the hinge rods, 50 disconnecting the wing braces, removing the wing top-plates, and finally knocking down or withdrawing the main mold sections and swinging the wing sections out of engagement with the wings of the header. In this 55 manner a complete, integral header is formed about the pipe end with outwardly diverging walls, preferably declining from the main wall of the header to the front ends, as shown.

Having thus fully described my invention, what I claim as new and desire to secure by Letters Patent is—

1. The combination in a header mold adapted to receive a pipe and of a main 65 wall section having the rear orifices to fit around a pipe end and a front plate to close said pipe end, said plate having cut-away portions, and separable wing sections hinged to said front plate adjacent the cut-away 70 portions.

2. The combination in a header mold, of a main section having rear and front walls and an orifice in the former to fit round a pipe-end held in contact with the latter, and hinged end walls; said front plate having cut-away portions, a pair of wing sections, each comprising a hinged plate, an additional side plate, a hinged front plate, and a top plate rigidly holding the two side 80 plates and front plate, and detachable braces connecting the wing sections and wall section.

In testimony whereof I affix my signature.

CHARLES F. BOND.
